UNITED STATES PATENT OFFICE.

SCOTT L. WILSON, OF REDDING, IOWA.

VEHICLE-TOP.

1,290,457.

Specification of Letters Patent.

Patented Jan. 7, 1919.

Application filed April 28, 1917, Serial No. 165,161.

Renewed November 1, 1918. Serial No. 260,721.

To all whom it may concern:

Be it known that I, SCOTT L. WILSON, a citizen of the United States, residing at Redding, in the county of Ringgold and State of Iowa, have invented certain new and useful Improvements in Vehicle-Tops, of which the following is a specification, reference being had to the accompanying drawings.

10 This invention relates to certain improvements in vehicle tops and has relation more particularly to a device of this general character especially designed and adapted for use in connection with automobiles or the like; and it is an object of the invention to provide novel and improved means whereby the top can readily and conveniently be lifted or elevated into operative position.

The invention consists in the details of 20 construction and in the combination and arrangement of the several parts of my improved vehicle top whereby certain important advantages are attained and the device is rendered simpler, less expensive and 25 otherwise more convenient and advantageous for use, all as will be hereinafter more fully set forth.

The novel features of the invention will hereinafter be definitely claimed.

30 In order that my invention may be the better understood, I will now proceed to describe the same with reference to the accompanying drawings, wherein—

Figure 1 is a view in side elevation illustrating an embodiment of my invention in applied position;

Fig. 2 is a fragmentary view in top plan of the device as shown in Fig. 1 with portions broken away;

40 Fig. 3 is a sectional view taken substantially on the line 3—3 of Fig. 1;

Fig. 4 is an enlarged fragmentary sectional view taken substantially on the line 4—4 of Fig. 1 and illustrating a connection 45 between a vertically disposed tubular member and the adjacent portion of a wind shield as herein embodied;

Fig. 5 is an enlarged sectional view taken substantially on the line 5—5 of Fig. 2;

50 Fig. 6 is a sectional view taken substantially on the line 6—6 of Fig. 5;

Fig. 7 is an enlarged fragmentary view partly in elevation and partly in section illustrating certain features of the elevating 55 mechanism as herein included; and

Fig. 8 is a fragmentary view partly in

top plan and partly in section of the structure illustrated in Fig. 7, the top or cover of the drum housing being omitted.

As herein embodied, B denotes a vehicle 60 body of any preferred type and which has pivotally engaged therewith, as at 1, the base 2 coacting in a conventional manner with the flexible top T. The rear edge of the top T is suitably secured, as indicated at 65 3, to the rear portion of the body B, while the forward or free end of said top T is provided with the transversely disposed bar 4 provided at its opposite ends with the forwardly directed extensions 6 suitably engaged with the top T for a purpose which is believed to be clearly apparent to those skilled in the art to which my invention 70 pertains.

Suitably positioned within the body B is 75 a housing H having in communication therewith at its forward end the tubular members M. The members M are provided adjacent the dash D of the body B with the oppositely directed lateral extensions 7 which are continued by the rearwardly and upwardly inclined portions 8 extending exteriorly of the body B through the sides thereof and terminating in the upstanding vertical members 9 arranged in transverse alinement 85 with the wind shield W or the like. Each of the members 9 is connected to the adjacent portion of the wind shield W through the medium of the clamps C, as particularly illustrated in Figs. 1, 2 and 4 and whereby 90 the members 9 are effectively maintained in requisite position.

Rotatably mounted within the housing H and disposed transversely thereof is a drum 10 around which is adapted to be wound the flexible members 11. A flexible member 11 is directed through each of the tubular members M and has its outer or free end provided with a fastening member 12 preferably of a hook type, which is 100 adapted to be detachably connected with an eye member 14 or the like carried by an end portion of the bar 4.

When the top T is in lowered position the hooks 12 are engaged with the eye members 105 14 and upon requisite rotation being imparted to the drum 10 the top T will be elevated to applied position as indicated in Fig. 1. In order to eliminate friction at the bends of the members M I find it of 110 advantage to rotatably mount at each of the bends of the members M an idle pulley 15

over which a flexible member 11 is passed, as is particularly illustrated in Fig. 8 of the accompanying drawings.

The drum 10 is fixed to a shaft 16 having one end portion extending exteriorly of the housing H and affixed to said extended portion of a shaft 16 is an operating member 17 herein shown as a conventional hand crank, whereby the requisite rotation may be imparted to the drum 10. The extended portion of the shaft 16 has also fixed thereto the toothed wheel 18 with which coacts a dog 19 pivotally engaged with the housing H at a point above the wheel 18. The dog 19 coacts with the wheel 18 to hold the shaft 16 against retrograde movement and also to maintain the top T in elevated position. When the top T is elevated into applied position the detent 20 pivotally engaged with the housing H is forced into contact with the dog 19 whereby said dog is held in engagement with the wheel 18 and said wheel 18 locked against rotation.

The wheel 18 is also in mesh with an idle toothed wheel 21 rotatably supported by the housing H and which has in contact with the toothed periphery thereof the rounded end 22 of the dog 23 pivotally engaged with the housing H. The rounded end 22 of the dog 23 is constantly urged toward the wheel 21 through the medium of the expandable member 24 herein disclosed as a conventional coil spring interposed between the dog 23 and a lug 25 extending outwardly from the adjacent side of the housing H.

When it is desired to lower the top T the dog 19 is thrown upwardly out of engagement with the wheel 18 so that the top T may be lowered by gravity. The dog 23 coacts with the wheel 21 to impose sufficient tension upon the members 11 to prevent too rapid lowering of the top T which otherwise would tend to injure certain of the parts.

The upper ends of the members 9 are closed and each closed end is provided with an opening or slot 26 through which a member 11 passes, and supported within the upper end of the member 9 and extending within said opening or slot 26 is an idle pulley 27 over which the member 11 passes, as is particularly illustrated in Fig. 5.

A side wall of each of the members 9 immediately adjacent the pulley 27 is provided

with a hinged door 28. After the top T has been lowered and the hooks 12 disengaged from the bar 4 the doors 28 are open and the hooks 12 engaged with the members 11 below the pulleys 27 so that the hooks 12 and the members 11 will be substantially entirely concealed when the doors 28 are returned to closed position.

From the foregoing description, it is thought to be obvious that a vehicle top constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice, except as hereinafter claimed.

I claim:

The combination with a vehicle body, of a top swingedly mounted on the body for movement in a vertical plane, a housing positioned within the body, tubular guideways in communication with the body and terminating in upstanding portions arranged at opposite sides of the body, a winding mechanism arranged within the housing, flexible members engaged with said winding mechanism and disposed through the tubular guides, rollers arranged in the upper extremities of the tubular guides over which the flexible members are directed, hook members carried by the outer extremities of the flexible members and detachably engageable with the top, and a door carried by the upper end portion of each of the tubular guides to afford means whereby the hook members of the adjacent flexible members may be engaged with the portion of said flexible member below the rope.

In testimony whereof I hereunto affix my signature in the presence of two witnesses.

SCOTT L. WILSON.

Witnesses:

O. L. FULLERTON,
W. C. SMITH.
